UNITED STATES PATENT OFFICE

HERMAN GILLIAN, OF COLUMBUS, OHIO

GLOVE

Application filed October 29, 1925. Serial No. 65,557.

This invention relates to gloves.

This invention has utility when incorporated in gloves of fabric base or lining and wear facing of leather reinforcement.

Referring to the drawings:

Fig. 1 is a view, with parts broken away, of an embodiment of the invention in a glove from the palm side;

Fig. 2 shows the glove of Fig. 1 from the back;

Fig. 3 is a detail view of the thumb back blanks of the facing of leather showing interfitting cutting economy;

Fig. 4 is a view of the thumb back lining blank as of fabric;

Fig. 5 is a view of the third finger back lining blank;

Fig. 6 is a blank of the facing for the palm and digit portion of the inside of the hand;

Fig. 7 is a blank of the cuff patch or base;

Fig. 8 is a view of a pair of blanks for the index finger back facing or fourchette;

Fig. 9 is a view of a pair of U-shaped fourchettes for the facing back of the second finger showing the interfitting relation for economical cutting;

Fig. 10 is a view of a pair of blanks for the third finger back or fourchette showing the interfitting cutting;

Fig. 11 is a view of a pair of blanks for the little finger back or fourchette showing the interfitting cutting economy;

Fig. 12 is a view of the lining blank for the palm with digits;

Fig. 13 is a view of the lining blank for the little finger;

Fig. 14 is a view of the lining blank for the second finger; and

Fig. 15 is a view of the blank for the gauntlet.

Lining blank has palm portion 1 with thumb inner side portion 2, index finger 3, and index finger back portion 4 therewith. Additionally, from the lining blank palm portion 1, there extends second finger lining 5, third finger lining 6, and little finger lining 7. The index finger back lining 4 has starting notch 8 as a guide in sewing assembly. Dotted portion 9 indicates the departure of the index finger back portion 4 from

the full back for the index finger with resultant saving in lining material. Second finger back lining blank 10 has starting indication points 8 with dotted portions 9 showing departure from full second finger back 55 form. Third finger back lining 11 has starting indication points 8 with dotted line portions 9 showing the departure of this blank from third full finger back form. Little finger blank 12 shows starting indication points 60 8, 13, with dotted portion 9 showing departure from full little finger blank with resultant saving in lining material in the back for this finger. Thumb back lining blank 14 has dotted portion 9 indicating the departure 65 from full thumb blank as the saving in lining material for the thumb. The full line portion (Fig. 4) near the dotted portion 9 discloses for this blank a straight side from adjacent the wrist terminus inclined from 70 the upper right and extending toward the extreme tip of the thumb. Accordingly this edge is inclined to a line which would extend from the mid-point of the wrist portion to the extreme tip of the thumb. Thumb back facing blank 15 is a J-shaped element and in the instance herein shown may be of leather. Palm facing 16 may also be of leather. Thumb front 17 may be integral with the palm facing 16 and integral with index finger 80 18, second finger 19, third finger 20, and little finger 21.

From index finger extension 22 there may be fourchette section 23 of J-form as a partial back for the index finger leaving the 85 finger knuckles clear and exposing the lining. Second finger back of U-fourchette 24, as well as U-fourchette 25 for the third finger back and U-fourchette 26 for the little finger back, protect the tips of the fingers as well as provide protection between the fingers for the full extent of the fourchettes, while the knuckle portions of the back of the fingers are shielded only by the cloth lining to thus maintain ample flexibility in use.

Closing up of the glove is an assembling of these fourchette and lining elements with the palm facing portions. Stitching 27 serves to engage marginal portions of the finger back linings in the narrow regions 100

and tack such lining spaced from the finger tip, while closing in seam 28 terminally tacks the fourchettes with the finger front facing portions as well as the finger front lining portions. These finger front lining portions are, accordingly, only terminally tacked. The narrowing of these finger front lining portions permits interfitting in cutting the blanks as shown in dotted lines in Fig. 12. 10 This means a saving in yardage. While the leather is usually cut from the fragmentary portions of hide, the interfitting features of the semi-U or J and the full U portions are features permitting economy in the cutting of such with the fourchette material in the flat with ready adaptation to the form of the finger backs. There is, accordingly, in the showing herein, economy in lining material, as well as in facing material cutting of the 20 blanks. The assembly of the fourchettes with the linings is simple. This is followed by single closing in seam 28 for assembling the fourchette and back lining with the front facing and lining. Thereafter, cuff patch 29 and gauntlet 30 may be assembled in completing the glove.

What is claimed and it is desired to secure by United States Letters Patent is:

1. A thumb back lining blank having a tip, 30 a wrist terminus, said blank on one side tapered outward from both the tip and the wrist terminus, and on the opposite side extending straight from adjacent the wrist terminus and inclined to a line from the mid-portion of the wrist to the extreme tip of the thumb lining blank.

2. A thumb back lining blank having a tip, a wrist terminus, said blank on one side tapered outward from both the tip and the wrist terminus, and on the opposite side extending straight from adjacent the wrist terminus and inclined to a line from the mid-portion of the wrist to the extreme tip of the thumb lining blank, a palm lining blank having an integral thumb lining portion for opposing said thumb back lining, said palm lining blank being provided with a crotch between the other fingers, finger back blanks, a facing for the glove including said finger back blanks, and stitching assembling said blanks and facing.

In witness whereof I affix my signature.

HERMAN GILLIAN.
